US00D853561S

(12) **United States Design Patent** (10) **Patent No.:** **US D853,561 S**
Guo (45) **Date of Patent:** **** Jul. 9, 2019**

(54) **IMPLANTATION DEVICE**

(71) Applicant: **Chengjun Guo**, Beijing (CN)

CN 304170302 * 6/2017
CN 107233665 10/2017
GB 2500893 * 12/2017 ..... A61B 5/09

(72) Inventor: **Chengjun Guo**, Beijing (CN)

(73) Assignee: **Chengjun Guo**

(**) Term: **15 Years**

(21) Appl. No.: **29/648,054**

(22) Filed: **May 17, 2018**

(30) **Foreign Application Priority Data**

Feb. 16, 2018 (CN) 2018 1 0158832

(51) **LOC (11) Cl.** **24-02**

(52) **U.S. Cl.**

USPC **D24/138**

(58) **Field of Classification Search**

USPC D24/138, 144, 145, 146, 140, 147, 133,
D24/112, 113, 130, 134, 135

(57) **CLAIM**

The ornamental design for an implantation device, as shown and described.

DESCRIPTION

FIG. 1 is a perspective view of a first embodiment of an implantation device showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof.

FIG. 8 is a perspective view of a second embodiment of the implantation device showing my new design;

FIG. 9 is a front view thereof;

FIG. 10 is a rear view thereof;

FIG. 11 is a left side view thereof;

FIG. 12 is a right side view thereof;

FIG. 13 is a top view thereof; and,

FIG. 14 is a bottom view thereof.

1 Claim, 14 Drawing Sheets
